INVENTOR
LAWRENCE A. DUNN
BY *Arthur L. Sles*
ATTY.

UNITED STATES PATENT OFFICE.

LAWRENCE A. DUNN, OF GARDEN VALLEY, CALIFORNIA.

CIGARETTE HOLDER.

Application filed June 21, 1926. Serial No. 117,491.

My invention relates to improvements in cigarette holders and the like wherein a sleeve is provided with a collar arranged to grip the end of a cigarette or cigar and to 5 readily release the same when desired.

The primary object of the present invention is to provide an improved holder for cigarettes, cigars, and the like.

Another object is to provide an improved 10 holder which will firmly grip the end of a cigarette or cigar while the same is being smoked and which will facilitate the removal of the stub from the holder when said cigarette or cigar has been consumed.

15 A further object is to provide an improved device which will facilitate the introduction of the end of a cigarette or cigar into the holder without damaging the same.

Another object is to provide an improved 20 holder which will readily receive and engage cigarettes or cigars of various sizes.

A still further object is to provide an improved holder of simple construction and which will be simple and efficient in operation. 25

I accomplish these and other objects by means of the improved device disclosed in the drawings forming a part of the present application wherein like characters of reference are used to designate similar parts 30 throughout the specification and drawings in which,

Fig. 1 is a side elevation of my improved holder showing the manner in which a cigarette is held therein.

Fig. 2 is an enlarged broken sectional detail showing the construction of the operating elements of the holder, and

Fig. 3 is a similar view showing the manner in which the sleeve is contracted to engage the end of a cigarette.

Referring to the drawings, my improved holder will be seen to consist of a bit of any suitable size or shape and constructed from 45 any suitable material, said bit being designated in general by the numeral 1. The forward end of the bit has a tapered recess 2 formed therein within which recess is fitted the inner end of a correspondingly tapered sleeve 3 flaring outwardly from the end of the bit and arranged to receive the end 50 of a cigarette 4 or the like. The outer end of the sleeve 3 has a plurality of longitudinally disposed splits 6 formed therein to permit the outer end of the sleeve to be normally expanded to receive the end of a

cigarette and to permit said end to be contracted to grip the cigarette as hereinafter more fully explained. The sleeve 3 is made of any suitable material affording a resilient 60 flexibility to the outer split end portion.

A collar 7 is slidably mounted upon the outer end of the bit 1 and preferably provided with an inwardly disposed flange 8 arranged to engage the sleeve 3. A longitudinally disposed slot 9 is formed in the collar 7 to receive a pin 11 secured upon the forward end of the bit 1 whereby the collar is normally slidably retained upon the bit and guided during a longitudinal movement thereon.

In operation, the collar 7 is initially moved rearwardly to its extreme releasing position as shown in Fig. 2 of the drawings, thereby permitting the split end of the 75 sleeve 3 to expand to normal flared position. The end of a cigarette or cigar may now be readily inserted into the outer end of the sleeve as shown in Fig. 3, the flared construction permitting said cigarette or cigar 80 to be inserted without marring or damaging the same in any way. After the end of the cigarette or cigar has been inserted into the sleeve 3, the collar 7 is moved outwardly as indicated in dotted lines in Fig. 3. As the 85 collar is moved outwardly the flange 8 presses against the flared end of the sleeve and compresses the split portion into firm gripping engagement with the end of the cigarette or cigar whereby the cigarette may 90 be firmly held.

When it is desired to release the butt of the cigarette or cigar, the collar 7 is moved rearwardly to disengage the sleeve 3 and permit the split end to be expanded by virtue of its own resiliency, thereby releasing the butt and permitting it to be readily shaken out of the sleeve.

The flaring outer end of the sleeve 3 is made of sufficient size to accommodate any 100 ordinary size of cigarette or cigar and permit the same to be firmly engaged without the necessity of crowding the end into the holder, thereby avoiding injury to the cigarette or cigar and insuring that the butt 105 may be easily released.

The inwardly disposed flange 8 is arranged to abut against the outer end of the bit 1, thereby defining the extreme rearward position of the collar 7 upon the bit 1. The 110 outward movement is normally limited by the engagement of the flange with the outer

portion of the sleeve 3. Thus in practice the longitudinal movement of the collar is limited by the flange, thereby preventing wear or injury to the guiding pin 11. The 5 flange 8 absorbs the wear resulting from the frictional engagement of the collar with the sleeve 3, thereby preventing ordinary wear from destroying the utility of the device.

The holder may, of course, be constructed 10 of any desired size and finished to obtain an attractive appearance. The specific details of construction are, of course, subject to modification in numerous ways without departing from the spirit of the invention. 15 I therefore do not wish to restrict myself to the specific details as herein disclosed, but desire to avail myself of any modifications which may fall within the scope of the appended claims.

20 Having thus described my invention what I claim as new and desire to secure by Letters Patent is,

1. A cigarette holder comprising a bit;

a sleeve connected to the end of the bit, said sleeve being longitudinally split along its 25 outer end to receive the end of a cigarette; and a collar slidably mounted upon the end of the bit and provided with an inwardly disposed flange engaging the outer end of the sleeve whereby the sleeve may be contracted 30 upon the end of the cigarette.

2. A cigarette holder comprising a bit; a sleeve connected to the end of the bit, said sleeve being longitudinally split and outwardly flared at its outer end; and a collar 35 slidably mounted upon the end of the bit and provided with an inwardly disposed annular flange engaging the outer end of the sleeve whereby the sleeve may be contracted to grip the end of a cigarette, said flange 40 being arranged to engage the outer end of the bit to limit the rearward movement of the collar along the bit.

In witness whereof I hereunto set my signature.

LAWRENCE A. DUNN.
